[57] **CLAIM**

The ornamental design for a water meter replacement plug, as shown and described.

DESCRIPTION

FIG. 1 is a perspective view of a water meter replacement plug showing my new design;

FIG. 2 is an end elevational view thereof, the opposite end being the same as the end shown;

FIG. 3 is a side elevational view thereof, the other sides being the same as the one shown; and

FIG. 4 is a fragmentary cross-sectional view thereof taken on line 4—4 of FIG. 2.

FIG. 1

FIG. 2

FIG. 4

FIG. 3
